UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MEASURED-SERVICE TELEPHONE SYSTEM.

Application filed November 17, 1920 Serial No. 424,747. Renewed May 22, 1926.

The present invention relates in general to measured service telephone systems, but more particularly to automatic party line measured service systems, and the principal object of the invention is the provision of a system of this kind wherein each station on a party line is provided with a meter at the exchange, and wherein each meter is adapted to be separately connected for registering calls whenever its associated station is calling.

The novel feature of the invention lies in the method of controlling the meter selection, in which a calling subscriber selects his meter for operation in the course of a preliminary act which he is required to perform in order to initiate the call.

The means by which the foregoing is accomplished will be described fully herein-after, reference being had to the accompanying drawings, in which Fig. 1 shows the preferred form of the invention, while Fig. 2 is a modification operating on the same general principles, but employing somewhat different apparatus at the exchange.

Referring first to Fig. 1, this is a circuit diagram of the usual form which shows sufficient of the apparatus in an automatic telephone system to enable the invention to be explained and understood. More specifically, the drawing shows a two party line comprising conductors 11 and 12 and having automatic telephone substations A and A' connected in bridge thereof, a second line extending to the automatic telephone substation A², and the exchange apparatus which is required to connect the two lines. This latter comprises the individual line switch C and the associated master switch D, first selector E, and the connector H.

The automatic telephones are of the usual type, each having the usual talking instrumentalities and a calling device for controlling the automatic switches. Each of the party line telephones A and A' is also provided with a push button whose function will be explained shortly.

The individual line switch C which is associated with the party line at the exchange is of the well known plunger type, and together with a plurality of similar line

switches is controlled in its trunk selecting operations by means of the master switch D. The selector and connector switches E and H are of the well known Strowger vertical and rotary type as regards their mechanical construction and are operated according to the two wire system of control. Line, selector, and connector switches of the type mentioned are well known and are fully shown and described in the book entitled Automatic Telephony, by Smith and Campbell, published by the McGraw-Hill Book Company in 1914.

The meters M and M¹ are associated with substations A and A¹, respectively, and may be located at any suitable point in the exchange. In order to select the proper meter for operation when one of the stations on a party line is calling, certain additional relays are provided in the line switch C, and in this respect the circuit of the line switch differs from the one ordinarily used. Otherwise, however, the line switch is of the ordinary construction.

The apparatus involved having been briefly described, its operation will now be explained somewhat more in detail, with a view to pointing out how the proper meter at the exchange is operated whenever one of the stations on the party line establishes a successful connection. For this purpose it will be assumed that the subscriber at substation A desires to obtain a connection with the subscriber at substation A². When the receiver is removed the calling device, transmitter, and receiver are bridged across the line in the usual manner, but contrary to the usual practice nothing happens at the exchange, for the two line relays 13 and 14 which are associated with line conductors 11 and 12, respectively, are both connected to the ungrounded pole of the exchange battery. The subscriber at substation A, therefore, is required to perform some other act before he can operate the line switch C and obtain access to a first selector switch, and this act consists in momentarily depressing the push button P which is conveniently located on his telephone instrument. When the push button P is operated the bridge across the line conductors 11 and 12 is

opened and ground is connected to the lower line conductor 11 thereby completing a circuit which includes the said line conductor, the normally closed cut-off springs 29 and 5 28 at the line switch C, and the winding of the line relay 13 to battery. Upon energizing, relay 13 closes a circuit at its armature 18 for the slow acting relay 16 which is accordingly energized also. Push button P 10 need be depressed only for an instant and when it is released ground is disconnected from line conductor 11 and the circuit of relay 13 is broken. This relay, therefore, de-energizes and breaks the circuit of relay 16, 15 but since the latter relay is slow acting it will not fall back immediately and a circuit is momentarily completed through the pull in winding 31 of the line switch as follows: from ground by way of resting contact of armature 19 and the said armature, working contact of armature 22 and the said armature, pull in winding 31 and through a normally closed contact at the master switch D to battery. Upon energizing, the pull in 20 winding attracts both the cut-off armature 33 and the plunger arm 34, the former being operated to disconnect the line conductors 11 and 12 from the windings of the line relays 13 and 14, respectively, while the latter forces 25 the bank springs 40, 41, 42, and 43 into engagement with contacts 44, 45, 46, and 47, respectively. By the engagement of bank springs 40 and 43 with contacts 44 and 47, the line conductors 11 and 12 are extended into 30 engagement with the trunk line conductors 48 and 50 which terminate in the windings of the line relay (not shown) of the selector E. The line and release relays in the selector are therefore energized, and the latter 35 relay connects ground to the release trunk conductor 49. Bank spring 41 being now in engagement with contact 45, a holding circuit is thus established for the holding winding 32 of the line switch C which is 40 thus energized in order to maintain the cut-off armature 33 and the plunger arm 34 in operated position. This holding circuit is 45 established before the slow acting relay 16 has had time to fall back. In addition to 50 the function explained, the holding circuit also serves to maintain ground potential on the private normal conductor 10 which extends to multiply connected test contacts in the banks of the connector switches which 55 have access to the party line, thus guarding the line against intrusion in the customary manner. Another circuit closed by the operation of the line switch is completed by the engagement of bank spring 42 with contact 60 46. When this contact is closed the operating magnet of the meter M is connected in series over conductor 23 with the left hand winding of relay 52, and the latter relay is 65 energized, being of such high resistance, however, that the meter M is prevented from

operating. Upon attracting its armature 55, relay 52 extends ground to the test contact associated with the selected trunk line in the test bank of the master switch D, whereby the said master switch is operated and the plungers of all the other idle line switches in the group are advanced into association with an idle trunk line.

The foregoing operations have occurred in response to the removal of the receiver 75 at substation A and the actuation of the push button P, and as a result of the latter act in particular the calling line has been extended by means of the line switch C into connection with an idle first selector switch, 80 which it has been assumed is the selector E. The calling subscriber may now operate his calling device in accordance with the digits in the telephone number assigned to substation A², and as a result the selector E and 85 a connector switch, which we will assume is the connector H, are operated in the well known manner to establish connection with the called line and signal the called subscriber. These operations are well known 90 and need not be explained in detail herein. It will be sufficient to say that when the selector E is operated and connects with the connector H, the trunk line conductors 48 and 95 50 are extended through to the windings of the line relay 71, which thereafter controls the operation of the connector switch. This relay also maintains a circuit for the slow acting release relay 72, which in operation maintains ground on the release trunk conductor 49, which is extended through to the connector at the same time as line conductors 48 and 50.

When the called party at substation A² 105 answers by removing his receiver a circuit is completed for the double wound back bridge relay 70, which upon energizing reverses the trunk conductors 48 and 50 as regards their connection to the windings of the double wound line relay 71, and therefore 110 reverses the direction of current flow in these trunk conductors.

This brings us to consideration of the means of actuating the meter M to register the call. The relay 51 in the trunk line extending to the selector E is an electropolarized relay which has a polarizing winding of high resistance and few turns through which current flows from the grounded release conductor 49 while the trunk line is in use. This winding and the right hand winding, 120 which is in series with conductor 48, are in opposition during the establishment of the connection and until the called subscriber answers, relay 51 therefore remaining inoperative. When the called subscriber answers, and current is reversed in the trunk conductors, the windings of relay 51 will assist each other and said relay will be operated. Having once pulled up relay 51 is 125 130

5 maintained in operated position by its left hand winding alone, and the right hand winding is short circuited at armature 53 in order not to interfere with the talking circuit. At its armature 54, relay 51 connects the low resistance right hand winding of relay 52 in parallel with the left hand winding of the said relay, and by this operation the current flow in the circuit of the operating 10 magnet of the meter M is sufficiently increased to cause the said magnet to energize. The meter M is thus operated to register the call.

15 Conversation may now proceed over the established talking circuit in the customary manner. Since relay 51 is held up by ground on the release trunk conductor 49 independent of the called subscriber no further operation of the meter can take place. When the 20 subscribers are through talking they will hang up their receivers, and the connection is released.

Having explained how the meter M is operated when a call is made from substation 25 A, the process of operating the meter M¹ when a call is made from substation A' may now be briefly described. Before proceeding it will be advisable to consider the wiring of the push buttons at the two substations, as these push buttons determine the 30 selection of the proper meters at the exchange. Push button P' at substation A' is exactly like the push button P at substation A, and is connected in the telephone circuit 35 in the same way. In the case of substation A' however the break contacts at the push button are short circuited, so that whenever the push button is operated both of the line conductors will be grounded, instead of only 40 the lower line conductor 11.

Suppose now that a subscriber at substation A' desires to make a call. The receiver is first removed, but without result, as explained in the previous case. The subscriber 45 will now operate the push button P' for an instant, thereby grounding both of the line conductors 11 and 12. As a result relays 13 and 14 of the individual line switch C are energized and the former relay closes 50 a circuit for the slow acting relay 16, which energizes and prepares a circuit for the pull in winding 31. Relay 14, upon energizing, closes a circuit for the slow acting relay 15 at its armature 17, and when the latter relay 55 pulls up it prepares a locking circuit for itself at its armature 20, and at its armature 21 shifts the meter control wire 23 into connection with the operating magnet of meter M¹. When the push button at substation A' is released 60 ground is removed from the line conductors and relays 13 and 14 will fall back and break the circuits of relays 16 and 15, respectively. Both the latter relays are slow acting, however, and before they have 65 time to deenergize the line switch C is op-

erated as explained hereinafore to establish connection with an idle trunk line, which we may assume to be the trunk line extending to the selector E. The line and release relays in the selector now pulls up and 70 ground is placed upon the conductor 49, with the usual results, and with the additional result in this case that a locking circuit for relay 15 is established which extends from the grounded release trunk conductor 49 by 75 way of bank contact 45, bank springs 41, contact springs 25 and 24, armature 20 and its working contact, and the winding of relay 15 to battery. Relay 15 will therefore 80 be held energized throughout the duration of the connection. The remainder of the operations which take place in establishing the desired connection are similar to those already described and need not be repeated. It will be evident that when the called subscriber answers and the polar relay 51 in the first selector trunk is operated, the meter M¹ 85 rather than the meter M will be actuated to register the call.

The modification of the invention which is 90 shown in Fig. 2 will now be explained. In this figure a party line is shown which comprises the line conductors 111 and 112 and the telephone substations A³ and A⁴. At the exchange the party line is provided with the 95 two plunger type line switches C³ and C⁴, thus differing in an essential respect from the party line shown in Fig. 1 which is only provided with a single line switch. The remainder of the apparatus however, comprising the trunk relays 151 and 152, the selector E', and the connector H' is the same as 100 shown in the other drawing. Meters M³ and M⁴ are associated with substations A³ and A⁴, respectively. 105

Each of the telephone substations is provided with a push button, these push buttons being indicated by the reference characters P³ and P⁴, respectively. The wiring at both telephones, including the wiring of 110 the push buttons, is exactly the same, and the selection of the meters at the exchange is controlled by a reversal in the line between the two stations.

Proceeding now with the explanation of the circuit operations, suppose that the subscriber at substation A³ desires to call a subscriber at substation A⁴. The receiver is first removed, and the subscriber will now 115 operate the push button P³ for an instant. As a result ground is placed upon line conductor 111 and a circuit is completed which extends by way of the said line conductor 111, through the normally closed cut-off springs 120 and 121 of line switch C⁴, normally closed cut-off springs 122 and 123 of line switch C³, and the winding of relay 113 120 to battery. Relay 113 is accordingly energized and establishes a circuit for the relay 114, which energizes in turn and prepares a 125 130

circuit for the pull in winding 115 of the line switch C³. When the push button P³ is released by the subscriber ground is removed from the line conductor 111 and relay 113 5 will deenergize and break the circuit of relay 114. Since the latter relay is slow acting, however, it will not fall back for a moment and a circuit is completed in an obvious manner for the pull in winding 115, it being 10 understood that the open main conductor 130 extends to battery at the master switch. By the energization of the pull in winding 115, the line switch C³ is operated in the usual manner to extend the calling party 15 line into connection with an idle trunk line, which will be assumed to be the trunk line extending to the selector E'. The line and release relays of the selector are then energized over the line circuit, and the latter relay places ground upon release trunk conductor 149, thereby establishing a holding circuit for the holding or cut-off winding 116 20 of the line switch C³. These operations, and the remaining operations by which the calling line is extended into connection with a desired called line are similar to the corresponding operations which have been described in connection with Fig. 1, and therefore will not be considered in further detail. 25 It will be sufficient to state that when the called subscriber answers, the electropolarized relay 151 in the selector trunk is operated and connects the right hand winding of the double wound relay 152 in parallel with 30 the left hand winding of the said relay. This increases the flow of current in the previously established meter control circuit, including the operating magnet of meter M³, and said meter is accordingly actuated to 35 register the call.

When the subscriber at substation A⁴ makes a call the operations are just the same as those described, except that when the push button P⁴ is depressed line conductor 112 45 will be grounded, instead of the line conductor 111. As a result a circuit is completed for the line relay 133 of line switch C⁴, which extends by way of the said conductor 112, cut-off springs 124 and 125 of line switch C³, cut-off springs 126 and 127 of line switch C⁴, and the winding of the line relay 133 to battery. Relay 133 is, therefore, energized and closes the circuit of relay 134, and these two relays operate jointly 50 when the push button P⁴ is released at the substation to bring about the energization of the pull in winding 135 of line switch C⁴. Thus it will be seen that when the subscriber at substation A⁴ makes a call the line switch C⁴ will be used rather than the line switch C³, and it will be evident then that meter M⁴ will be connected for use and will be operated to register the call when the 55 called subscriber answers.

Having described my invention, what I

consider to be new and desire to have protected by Letters Patent will be pointed out in the appended claims.

What I claim as my invention is:

1. In a telephone system, a party line, a meter at the exchange for each station on the line, a push button at each of said stations, line extending switching mechanism at the exchange responsive to the operation of the push button at a calling station, and mechanism controlled in accordance with the push button which is operated for selecting the proper meter to register the call. 75

2. In a telephone system, a party line, switching mechanism at the exchange for extending the line when calling, a push button at each station on the line for operating said mechanism, a meter at the exchange for each of said stations, and means controlled by the push button which is actuated when a call is made for determining which of said meters will be operated to register the call. 80

3. In a telephone system, a party line, switching mechanism at the exchange for extending the line when calling, a push button at each station on the line for operating said mechanism, a meter at the exchange for each of said stations, a relay for determining which of said meters will be operated when either station makes a call, and means for operating said relay only when the push button at a particular station is actuated. 90

4. In a telephone system, a two party line, a switching device at each station on the line, the device at one station being adapted to ground both sides of the line while the device at the other station is adapted to ground one side only, a meter at the exchange for each of said stations, means requiring the subscriber at each station to actuate the device thereat only after the instrumentalities of a station are placed in talking condition to make a call, and means at the exchange dependent on which device is operated for determining which meter 100 will be operated to register the call. 105

5. In a telephone system, a two party line, a switching device at each station on the line, the device at one station being adapted to ground both sides of the line while the device at the other station is adapted to ground one side only, after a call has been initiated from the respective stations, a meter at the exchange for each of said stations, a switch mechanism responsive to ground on either one or both sides of the line to extend the line and means operated in response to a ground on both sides for selecting the meter corresponding to the station whose device grounds both sides of the line. 115 120

6. In a telephone system, a two party line, a switching device at each station on said line, one of which is operated to ground one side of the line, and the other to ground both sides of the line, a meter for each of said 125 130

stations, the operating circuit of the meter of said first mentioned line being normally extended thereto, a switch for extending said line, a quick and a slow acting relay responsive to the grounding of one side of the line to operate said switch, and a quick and a slow acting relay responsive to the ground-

ing of both sides of said line to break said normal meter circuit and to extend said circuit to the other of said meters.

10

Signed by me at Chicago, Cook County, Illinois, this 5th day of Nov., 1920.

BERNARD D. WILLIS.
